UNITED STATES PATENT OFFICE.

JOHN BOSWELL AND EUGENE PEARL, OF NEW YORK, N. Y.

DOCUMENT-FILE.

1,079,100.

Specification of Letters Patent. Patented Nov. 18, 1913.

Application filed April 14, 1913. Serial No. 761,108.

To all whom it may concern:

Be it known that we, JOHN BOSWELL and EUGENE PEARL, citizens of the United States, and residing, respectively, in the city 5 of New York, county and State of the same name, have invented certain new and useful Improvements in Document-Files, of which the following is a specification.

This invention relates to improvements in 10 document files and particularly to that class adapted to be disposed within drawers or other suitable inclosures in which the papers are held vertically.

One object is to provide such files so arranged 15 that documents placed in folders properly tabbed or indexed can be found with unusual readiness and withdrawn or entered without waste of time.

Another object is to provide a file that 20 while effectually supporting papers, offers no impediment to their removal, cannot mutilate, mark or crease the same and which occupies a negligible amount of space.

A third object is to provide means for 25 filing that are practically indestructible, being fireproof, capable of long and continuous service and which may be readily moved with their contents intact from place to place as a unit. And finally, to so arranged 30 the several parts that the whole may be collapsed into a compact form when empty, as in storage and transportation.

These and other objects are attained by the novel construction and arrangement of 35 parts hereinafter fully described and shown in the accompanying drawings, forming part of this specification, and in which:—

Figure 1 is a perspective view of the entire apparatus, partially filled in order to 40 illustrate its application. Fig. 2 is a similar view of the apparatus in collapsed or "knocked down" condition. Fig. 3 is a sectional view taken through one of the partition plates, showing the manner of securing 45 the resilient members, drawn to an enlarged scale. Fig. 4 is a similar view showing the plate hinging means, also drawn to an enlarged scale and, Fig. 5 is a fragmentary perspective view showing a modification in construction.

The apparatus consists of two strips 10 of

sheet metal adapted to rest upon the bottom of any desired drawer, box or other inclosure that will contain the papers to be filed; these strips are made of such length 55 as to nearly or quite make contact with the front and rear end walls so that the device may not move longitudinally therein. At intervals the material is pressed so as to form open loops 11 upon their upper surface to admit of the passage therethrough of rods 12 which extend lengthwise through the semi-circular turned lower edges 13 of the thin metal partition plates 15, a slot or recess 14 being cut out of the described 60 turned edge to accommodate the loops 11. The tops of the plates 15 are formed in a similar manner and have extending into the bead 16 so formed other rods 17 which also pass through the side bars 18, the latter being formed with openings to receive the rods which are distanced apart so as to register with the lower rods 12 and may be upset at their ends so as to be retained in position; these side bars 18 are preferably made of 65 L shaped sections, the outwardly turned member 18' extending over the edge of the drawer or case. Thus it will be seen that the apparatus consists of a plurality of plates hinged to a pair of members, common 70 to all at their lower edges, and pivotally connected with another pair of members at their upper edges in such manner that the plates may assume nearly a horizontal position as well as stand vertically.

The beading at both top and bottom of the plates provides for the requisite stiffness and at the same time presents a smooth surface against which the papers, which the file may receive, can contact without detriment. It will be obvious that the upper rods 75 17 may take the form of relatively short members and need not necessarily pass entirely through the upper beading.

In order to hold the plates erect, rods 20 95 are provided at each side, the same having an upper bent portion 21 formed to pass through one of the openings in the side bars 18, and into the beading on that plate where, if properly fitted, it will act as a 100 pivot in place of one of the mentioned rods 17; the other end is also bent in like man-

- 22
- ner as at 22 and removably engages for a short distance within the open end of the bead formed at the bottom of a plate remotely located so that the rods 20 form 5 angularly disposed struts, holding the plates vertical when desired, or if the bent portion 22 be withdrawn, allow the apparatus to collapse.
- In order to maintain the filed papers in 10 an erect position irrespective of the quantity of contents disposed in any one compartment formed between any two adjacent plates or between the end plates and the inclosing receptacle, flat elliptical 15 springs 25 are secured in pairs on both sides of each plate, the springs being entirely unconfined at their lower extremities 26 which slide freely on the plate surface and being so formed as to nearly contact at 20 their centers with adjacently disposed springs on succeeding plates; these springs are held in loops 28 on one side, and 29 on the other, formed by pressing the material of the plates in opposite directions until after insertion of the spring ends when the 25 loops are forced inwardly toward the plate, thereby firmly gripping the springs and holding the ends securely against movement in any direction.
- 30 In the modification shown in Fig. 5 the plates 30 are formed with beads 31 and 32 at the top and bottom respectively and present true, substantially unbroken parallelograms, the upper side bars 33 are substantially the same as those before described 35 and are secured in like manner; at the lower edges are angles 34 through which extend rods 35 practically the same as at the top; in this case the inturned member 36 of the 40 angle acts as a support for the documents and in addition, a flat rectangular bar 37 may be passed through an appropriate opening in the plates forming in effect a grate-like flooring.
- 45 From the foregoing it will be evident that the device presented may be readily constructed and is of such simple nature that an extended description of its application and use is not necessary; it may be pointed 50 out however, that in changing files it is only needed to remove the apparatus as a whole and that in shipping, it can be closed compactly, the elliptical springs being susceptible of assuming a completely flat position 55 between the plates when the latter are pressed together.
- Having thus described our invention what we claim as new and desire to secure by Letters Patent, is:—
- 60 1. A file comprised of base members, a plurality of plates hinged transversely thereto at their lower edges, and a pair of oppositely disposed rails pivotally attached at the upper corners of said plates in such manner as to present unobstructed openings 65 therebetween extending the full length of said plates.
2. A file comprised of one or more base members, a plurality of plates hingedly connected transversely of said base members, 70 rails pivotally engaging said plates exteriorly of their side edges at their upper outer corners and means for fixedly holding said rails with respect to said base members, said holding means being pivotally engaged 75 at each end thereof.
3. In a file, the combination with longitudinally disposed base members and side rails parallel therewith, of plates pivotally engaging at opposite edges with said base 80 members and said rails respectively; elliptic springs disposed in pairs on both sides of each plate, said springs being attached at one end and struts so combined with said rails and said plates as to hold the latter in 85 vertical position with respect to said base members or to allow the device to be collapsed.
4. In a device of the character described, in combination with supporting elements, 90 of a plurality of plates, integrally formed loops raised on opposite sides of each plate and flat elliptical springs secured in said loops, a portion of each spring being embraced in the depression formed by the oppositely disposed loop.
5. In a file, the combination with base members, loops formed integrally therewith, a plurality of plates, said plates having beaded upper and lower edges, rods passing 100 through the lower beadings and said loops, rails at the upper corners of said plates, said rails being perforated at intervals agreeing with said loops, rods passing through said perforations and upper beadings and struts 105 arranged to maintain said rails in fixed relation to said plates, one end of said struts being disengageable.
6. In a file, the combination with a plurality of plates, beaded at the top and bottom, of a pair of angularly formed rail elements pivotally connected at the top edges of said plates, a second pair of angularly formed rail elements pivotally connected at the bottom edges of said plates, the latter 115 elements having an inturned portion acting as a partial flooring below said plates.
7. A file having an open top and comprising spaced plate members, rails pivotally attached at the outer upper edges thereof, 120 and members constituting a grated flooring, said members being pivotally engaged along the bottom edges of said plate members.
8. An open topped document file comprising a plurality of plate members spaced 125 from each other, rails pivotally attached at

the upper outer corners of said plates and strip members pivotally attached at the bottom edges of said plates, said rails and said strip members extending outwardly beyond the end plates at the front and back of the file.

In testimony whereof we have signed our

names to this specification in the presence of two subscribing witnesses.
